United States Patent Office.

CHARLES P. McGIMSEY, OF MEMPHIS, TENNESSEE.

Letters Patent No. 98,179, dated December 21, 1869.

IMPROVED SOAP.

The Schedule referred to in these Letters Patent and making part of the same.

To all whom it may concern:

Be it known that I, CHARLES P. McGIMSEY, of the city of Memphis, county of Shelby, and State of Tennessee, have invented an Improvement in Compounding Soap. I do hereby declare that the following is a full and exact description thereof.

The nature of my invention consists in making, from three of Colgate's preparations, a cheap, economical soft soap, for washing and all other uses, it having proven in actual tests that it will do more work, and better, than when any of them (its compounds) is used separately.

To enable others skilled in the art to make and use this my invention, I will proceed to describe its construction and operation.

I take—

No. I, Colgate's No. 1 extract, (soap,) ten and one-half pounds;

No. II, Colgate's No. 1, (soap,) twenty-one pounds;

No. III, Colgate's No. 2, (sulpho-nitro potassa,) fourteen pounds;

No. IV, water, two hundred and ninety-nine pounds,

which will make three hundred and forty-five pounds soap of proper consistency, after it has been boiled and stirred till all is thoroughly mixed.

These proportions must be closely adhered to, as the least variation will entirely change the whole compound.

This soap is rubbed on the clothes when dry, then washed and rinsed.

In the washing of paint, it is first placed upon the parts to be washed; then the parts are to be washed and rinsed.

For the skin it has no equal; also when used as a shampoo. It is also good in cutaneous diseases for man or beast.

What I claim as my invention, and desire to secure by Letters Patent, is—

The herein-described compound of Colgate's soap and extracts, as described.

CHARLES P. McGIMSEY.
